UNITED STATES PATENT OFFICE.

JOHN S. TIMMONS, OF GERMANTOWN, PENNSYLVANIA, ASSIGNOR TO TIMMONS RADIO PRODUCTS CORPORATION, OF PHILADELPHIA, PENNSYLVANIA, A CORPORATION OF PENNSYLVANIA.

DESIGN FOR A LOUD SPEAKER OR SIMILAR ARTICLE.

Application filed May 11, 1925. Serial No. 13,391. Term of patent 14 years.

To all whom it may concern:

Be it known that I, JOHN S. TIMMONS, a citizen of the United States, residing at Germantown, in the county of Philadelphia and State of Pennsylvania, have invented a new, original, and ornamental Design for Loud Speaker or Similar Article, of which the following is a specification, reference being had to the accompanying drawing, forming part thereof.

Figure 1 is a front view of my loud speaker showing my new design; Fig. 2 is a plan view of the supporting base of the cone speaker taken on line 2—2 of Fig. 1; and Fig. 3 is a side view of the loud speaker on a reduced scale showing my new design.

I claim:

The ornamental design for a loud speaker or similar article as shown.

JOHN S. TIMMONS.
